[57] **CLAIM**

The ornamental design for a golf putter head with golf ball retriever, as shown and described.

DESCRIPTION

FIG. 1 is a top front right side perspective view of a golf putter head with golf ball retriever showing my new design;
FIG. 2 is a right side elevational view thereof;
FIG. 3 is a left side elevational view thereof;
FIG. 4 is a front elevational view thereof;
FIG. 5 is a rear elevational view thereof;
FIG. 6 is a top plan view thereof; and
FIG. 7 is a bottom plan view thereof.

The dashed lines in FIGS. 1-5 show a shaft which is not part of the present design.

The solid black ring disclosed on FIGS. 1, 6 and 7 indicates the color black.
